BED

Carl L. Otto, New York, N.Y., assignor to Heywood-Wakefield Company, Gardner, Mass., a corporation of Massachusetts

Application August 10, 1959, Serial No. 57,111

Term of patent 7 years

(Cl. D5—4)

Fig. 1 is a perspective view of a bed embodying my new design;

Fig. 2 is a sectional view on the line 2—2 of Fig. 1, but on a somewhat larger scale;

Fig. 3 is a vertical sectional view on the line 3—3 of Fig. 1, but on a larger scale; and

Fig. 4 is a vertical sectional view on the line 4—4 of Fig. 1, but on the scale of Fig. 3.

The dominant features of the design are the parts shown in full lines.

I claim:

The ornamental design for a bed, substantially as shown and described.
